(57) **CLAIM**

The ornamental design for a handle for medical devices including surgical retractors, as shown and described.

DESCRIPTION

FIG. 1 is a perspective view of the handle for medical devices including surgical retractors showing my design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The dot-dash broken lines and evenly spaced broken lines immediately adjacent the shaded areas represent the bounds of the claimed design while all other broken lines are directed to environment and are for illustrative purposes only; the broken lines form no part of the claimed design.
